DESIGN FOR A CHILD'S SPOON

Roland S. Claflin, Park Ridge, Ill.

Application March 15, 1947, Serial No. 137,631

Term of patent 14 years

(Cl. D54—12)

To all whom it may concern:

Be it known that I, Roland S. Claflin, a citizen of the United States, residing at Park Ridge, in the county of Cook and State of Illinois, have invented a new, original, and ornamental Design for a Child's Spoon, of which the following is a specification, reference being had to the accompanying drawing, forming part thereof.

Figure 1 is a plan view of a child's spoon, showing my new design;

Figure 2 is a side view of the spoon;

Figure 3 is a bottom view of the spoon;

Figure 4 is a view looking at the bowl end of the spoon; and

Figure 5 is a view looking at the handle end of the spoon.

I claim:

The ornamental design for a child's spoon, as shown.

ROLAND S. CLAFLIN.
